SLITTING MACHINE

Gerald Strecker and Theodor Göckel, Darmstadt,
GermanyApplication September 25, 1935, Serial No. 41,979
In Germany September 27, 1934

4 Claims. (Cl. 164—60)

This invention relates to slitting machines for cutting a web or width of paper, fabric or the like longitudinally into a plurality of strips, of the kind in which the web is fed to a plurality of 5 coating pairs of rotary circular knives or cutters.

In the usual longitudinal slitting machines of the aforesaid kind, the knives or cutters are located on separate shafts, either the lower knives being mounted on one shaft and the upper knives 10 on another, or one set of knives being mounted on one shaft and the other knives being individually carried by means of separate holders by a second shaft. If the width of the strips into 15 which the knives cut the sheet of paper has to be altered, it is clear that all the coating lower and upper knives must be adjusted on their shafts which is generally effected by first shifting the lower knives, or the upper knives, into the new 20 positions and fixing them and then pushing the upper, or lower, knives against them and likewise fixing them. In the case of longitudinal slitting machines with numerous cutters, this is an operation which takes considerable time during 25 which the machine is not able to work and must be at rest.

A primary object of the present invention is to reduce this work and therefore also the loss of time associated with it quite considerably and to enable the cutters to be displaced while the longitudinal cutter is running.

According to the present invention, both knives of each coating pair of cutters are fitted to a common holder which is displaceable transversely to the direction of travel of the web and comprises 35 two parts, on each of which one of the knives of each pair is revolvably mounted and which are connected by or integral with a bent or curved member which is located behind the cutters in the direction of travel of the web and passes through 40 the slit produced by the cutters in the web and is so shaped that the edges of the two adjacent strips which slide along it are bent out of the plane in which the web is fed to the cutters.

One form of construction of the new slitting machine is illustrated by way of example in the accompanying drawing, in which:—

Figure 1 is a side elevation partly in section.

Figures 2 and 3 are elevations viewed from the left- and right-hand side of Figure 1 respectively.

Figure 4 shows on a larger scale part of the members connecting two adjacent knife holders and the form which the strips assume on sliding along them.

Figure 5 is a cross-section on the oblique line 5—5 in Figure 4 seen from the left, and

Figures 6 and 7 show respectively two further cross-sectional forms of the said members and the forms which the strips assume as they slide 5 along them.

Referring to the drawing, the upper knife A and the lower knife B of which, in the construction shown in the drawing, the former is of disc-shape and the latter of cup-shape, are fixed on 10 pins C, D respectively which are mounted in the upper part E and the lower part E¹ respectively of the knife holder. The upper knife A which is driven by friction from the lower knife B can be removed from or applied against the lower knife 15 by turning a lever C¹. The pin C is further fitted in such a manner that it can be adjusted relatively to the pin D in a vertical direction. This adjustment is known and is therefore not illustrated in the drawing.

The upper and lower parts of the knife holder are connected by a cranked bracket or bent piece E² which, in the direction of travel of the web F, is situated behind the knives A, B and passes through the slit produced by the knives in the web. The bent piece E² is shaped in such a manner (Figures 3 and 4) that, of the two strips F¹ which slide along it, the adjacent edge of one strip is bent upwardly and that of the other downwardly out of the plane in which the web F is fed to the knives A, B. The knife holder can slide on the one hand on the driving shaft G, which is situated transversely to the direction of travel of the web F, by means of a sleeve or jacket E³ which is provided on its lower part and embraces the driving shaft, and on the other hand with its foot E⁴ on a guide bar H which is fixed in the frame of the machine. The under-side of the latter is provided with teeth H¹ in which a toothed wheel J, which is fitted on the foot E⁴ of the knife holder 40 and is revolvable by a hand wheel N, engages. The guide rod H also contains a scale H² in front of which a pointer K on the foot E⁴ of the knife holder moves. The pointer can be adjusted on the foot E⁴ in accordance with the wear of the 45 lower knife B.

With the lower knife B, a toothed wheel L is rigidly connected and this meshes with a toothed wheel M which is journaled in the lower part E¹ of the knife holder, and through which the 50 driving shaft G is carried in such a manner that the wheel is displaceable on the shaft but is not revolvable relatively to it.

By rotating the hand wheel N, the knife holder with the two knives A, B can be displaced on 55

the guide bar H whereby the sleeve E³ as well as the toothed wheel M slide along the driving shaft G.

- 5 In the forms of construction according to Figures 6 and 7, the bent part E² connecting the upper and lower part of each knife holder is provided on each side with a tapered rib E⁵ by which the edges of the two strips F¹ which slide along the ribs are bent upwardly out of the plane in which the web is fed to the knives.
- 10 10 In the form of construction according to Figure 7, loose rollers O are further provided on the bent parts E^{2x} which rollers press the upwardly bent edges of the strips against the parts E^{2x} and guide them along these parts.
- 15 We claim:—

1. A machine for slitting a travelling paper web, comprising a plurality of pairs of slitting wheels, a separate support for each pair of wheels 20 and a transverse guide for adjustably carrying said supports, each of the latter consisting of a substantially U-shaped frame supporting said wheels in its forward portion, the closed end of said frame having a longitudinally disposed guiding portion to offset the cut edges of the paper as the said cut edges pass the frame.
2. A machine for slitting a travelling paper web, comprising a plurality of pairs of slitting wheels, a separate support for each pair of wheels 25 and a transverse guide for adjustably carrying said supports, each of the latter consisting of a substantially U-shaped frame supporting said wheels in its forward portion, the closed end of said frame having a longitudinally disposed guiding portion to offset the cut edges of the paper and idlers adapted to press the deflected paper edges against said guiding portion as the said cut edges pass the frame.
- 30

substantially U-shaped frame supporting said wheels in its forward portion, the closed end of said frame being inclined at an angle to the plane traversed by the paper web, to form longitudinal guide ways to offset the cut edges of the paper, as the said cut edges pass the frame.

3. A machine for slitting a travelling paper web, comprising a plurality of pairs of slitting wheels, a separate support for each pair of wheels and a transverse guide for adjustably carrying 10 said supports, each of the latter consisting of a substantially U-shaped frame supporting said wheels in its forward portion, the closed end of said frame being substantially vertical and having transversely inclined longitudinal tracks to 15 offset the cut edges of the paper, as the said cut edges pass the frame.

4. A machine for slitting a travelling paper web, comprising a plurality of pairs of slitting wheels, a separate support for each pair of wheels 20 and a transverse guide for adjustably carrying said supports, each of the latter consisting of a substantially U-shaped frame supporting said wheels in its forward portion, the closed end of said frame having a longitudinally disposed guiding portion to offset the cut edges of the paper and idlers adapted to press the deflected paper edges against said guiding portion as the said cut edges pass the frame.
